SNAP SWITCH

James M. Brady, Wantagh, N. Y., assignor to
Servomechanisms, Inc., a corporation of New
York

Application October 1, 1952, Serial No. 312,539

15 Claims. (Cl. 200—67)

1

The present invention relates to switches for controlling electric circuits and more particularly to small switches of the type adapted to operate with a snap action in response to relatively minute movements of an actuating member. The invention comprises a novel switch of the above indicated character which is extremely sensitive, of simple construction, and adaptable to a wide variety of uses. The new switch is positive in action, requires few parts, insures relatively wide contact spacing in open circuit position, and may be readily coupled to various types of actuating elements.

Briefly, the new switch comprises a movable contact carrying arm which is carried by crossed threads such as wires or ribbons, that are under longitudinal tension, the threads crossing at points laterally spaced from the arm. The crossing of the tensioned threads is such that the contact arm will pivot with a snap action from one position to another about a natural axis when but slight pressure is applied to a thread at or near a cross-over point or to the contact arm or to a part carried thereby. The switch may also be actuated by relative movement of the ends of the threads, as by rotation of a wall or arm to which the ends are anchored under tension. The invention includes also a rapid action sequential snap switch which is built up from the above briefly described switch. In the sequential switch the contact arms are all supported by the tensioned threads, the threads crossing between each arm and the pivotal movement of an arm serving to actuate a succeeding arm.

For a better understanding of the new switch and the various features of novelty thereof, reference may be had to the accompanying drawings, of which—

Fig. 1 is a perspective view of a snap switch embodying the invention arranged as a single pole, double throw switch;

Fig. 2 is a view similar to Fig. 1 but illustrating a double pole, double throw switch;

Fig. 3 is a side view of a hermetically sealed switch representing the presently preferred embodiment of the invention;

Figs. 4 and 5 are vertical and horizontal longitudinal sections, respectively, of the switch of Fig. 3, Fig. 5 being a section taken on the line 5—5 of Fig. 4;

Fig. 6 is a transverse section taken on the line 6—6 of Fig. 4;

Fig. 7 is a perspective view of a switch embodying the invention and representing a modification; and

Fig. 8 is a perspective view of a sequential switch embodying the invention.

2

The principle of operation of the new switch may best be understood by reference to the relatively simple construction illustrated in Fig. 1. In this embodiment the switch comprises two longitudinal beams 2 and 4 connected at their ends by cross beams 6 and 8 to form a rectangular framework, a contact arm 10 of conducting material, and tensioned wires 12 and 14 anchored at their ends to the beams 2 and 4 and floatingly supporting the arm 10. An end of each of the wires 12 and 14 is welded or otherwise secured to the beam 2 under tension, the points of attachment of the ends of the wires to the beam 2 being near the ends of the beam. The contact arm 10 has two transverse passages 16 and 18 therethrough, spaced from the center of the arm. Wire 12 extends from its point of attachment with the beam 2 through the passage 18 of arm 10 and is secured as by welding at its other end to the beam 4 at a point spaced from the cross-beam 6 by a distance substantially equal to that by which the point of attachment of the other end to the beam 2 is spaced from the cross-beam 6, the wire 12 thus being disposed in substantially V-form. Similarly, wire 14 is welded or otherwise secured under tension to the beam 2 adjacent the cross-beam 8, passes through the aperture 16 in the contact arm 10, and is secured at its other end to the beam 4 adjacent the cross-beam 8, the stretch of wire 14 between beam 2 and contact arm 10 passing under the corresponding stretch of wire 12 and in the stretch between the contact arm 10 and the beam 4 passing over the corresponding stretch of wire 12. The contact arm 10 is thus floatingly supported by the wires 12 and 14. Mounted on the cross-beam 6 adjacent the end of the contact arm are a pair of brackets 20 and 22 carrying adjustable fixed contacts 24 and 26 respectively, positioned for engagement with a contact 28 carried on the end of arm 10. Each of the brackets 20 and 22 is insulated from the frame by suitable insulation 30. On the cross-beam 8 are mounted brackets 32 and 34 carrying adjustable contacts 36 and 38 respectively, for engagement with a contact 40 on the adjacent end of the contact arm 10. Brackets 20 and 22 carry suitable terminals, of which only terminal 42 on bracket 20 is visible in the drawing, and bracket 32 carries a terminal 44 for connection of an external lead thereto.

With the above described construction the tension in the wires 12 and 14 on the side of the contact arm of beam 2 creates a couple tending to rotate the arm in a counter-clockwise direction as viewed in Fig. 1, about an axis intermediate the passages 16 and 18, whereas the tension in the

wires 12 and 14 on the side of the contact arm of beam 4 creates a couple tending to rotate the arm about the same axis but in a clockwise direction. If the distances between the wires 12 and 14 at the cross-over points, indicated at A and B, were equal, these opposing couples would be equal, assuming equal tension in the wires, and the contact arm would be in unstable equilibrium. The slightest departure from such unstable position in either direction of rotation increases the couple tending to rotate the arm in such direction. Hence the arm will continue to rotate until stopped by the fixed contacts or stops carried by the framework. To reverse the position of the contact arm it is only necessary to reverse the relative spacing of the wires at the cross-over points, thereby relatively increasing the couple acting on the arm in the desired direction. Thus the switch may be actuated by pressure upon either end of the contact arm 10 or by pressure upon a wire 12 or 14 at or near a crossing point. In the particular embodiment of the invention illustrated in the drawing, the actuating means is shown as a bifurcated member 46, the ramifications 48 and 50 of which span the crossing point A of the wires 12 and 14 intermediate the beam 2 and the contact arm 10. When the member 46 is moved downwardly, the spacing between wires 12 and 14 at point A is decreased, reducing the couple tending to cause counterclockwise rotation of the arm and permitting the couple exerted by the wires 12 and 14 on the far side of the arm to rotate the arm in a clockwise direction, bringing contact 28 into engagement with fixed contact 24 and contact 40 into engagement with fixed contact 38, the arm moving with a snap action upon passing through its equilibrium position. In this position of the contact arm a circuit will be closed from the external lead connected to terminal 44 to the external lead connected to the terminal 42 carried by bracket 20. Depending upon the initial relative spacing of the wires at the cross-over points A and B, the arm will either remain in the described position after the actuating member 46 has been raised or will snap back to its initial position.

If the spacing at point A is originally substantially greater than that at point B, arm 10 will be biased into the position shown in the drawing, that is, with contacts 28 and 26 in engagement and contacts 40 and 36 in engagement. Lowering of member 46 will cause arm 10 to reverse its position. Upon raising of the member 46 under this initial condition, the arm will return to its biased position unless the travel of the arm has been sufficient to make the spacing at point B greater than at point A. In this latter case, as in the case when the original spacings at points A and B are about equal, the contact arm will stay in either position until positively actuated into the opposite position.

If the arm thus remains in the position to which it has been actuated by member 46 and it is desired to reverse its position, the actuating member may be moved to the dotted line position shown in Fig. 1 and depressed to engage and depress the wire 14 at the crossing point B. Decrease of the spacing at point B will cause counter-clockwise rotation of the contact arm and closing of the contacts 28 and 26. The same result could be obtained by depressing wire 14 at point A to increase the spacing at this point.

As will be apparent from the above description, the operation of the above described switch depends upon the initial adjustment of the fixed

contacts or stops and upon the initial spacing of the wires 12 and 14 at the cross-over points. Relatively minute pressure upon a cross wire is sufficient to disturb the equilibrium of the contact arm 10 and cause actuation of the switch. By suitably insulating the brackets 32 and 34 and connection of external leads thereto, the single pole, double throw switch of Fig. 1 could be changed to a two-point make and break switch for two separate circuits, one circuit being from bracket 32 to bracket 22 and the other circuit being from bracket 34 to bracket 20.

The switch illustrated in Fig. 2 is of substantially the same construction as that described in connection with Fig. 1, and therefore similar parts have been identified with like reference numbers but with a prime annexed thereto. In Fig. 2, however, the framework comprising the longitudinal beams 2' and 4' and cross-beams 6' and 8' is of insulating material, as is also the contact carrying arm 10'. In this embodiment of the invention the contacts 28' and 40' carried at the ends of the contact arm 10' are connected through flexible leads 52 and 54 respectively to external circuits, as is each of the brackets 20', 22', 32' and 34'. With this arrangement the switch operates as a double pole, double throw switch. In one position of the arm 10' lead 54 is connected through contact 40' to bracket 34' and lead 52 is connected through contact 28' to bracket 20', whereas in the other position of the contact arm lead 54 is connected to bracket 32' and lead 52 is connected to bracket 22'. No actuating means is illustrated in Fig. 2 but it will be apparent that a member such as the member 46 of Fig. 1 could be employed or a finger engaging contact arm 10' at a point remote from its center could be employed.

The preferred embodiment of the invention in a practical commercial form is illustrated in Figs. 3 to 6, to which reference may now be had. In this embodiment of the invention the entire switch is enclosed within a hermetically sealed container and actuated externally by an arm mounted for slight pivotal motion. The entire device can be made in a small size, for example within a casing 2 1/2 inches long by 3/4 inch wide and under an inch high. A switch of such dimensions may be used to control circuits carrying up to about 20 amperes, with the voltage across open contacts of the order of 120 volts. The external casing of the switch of Figs. 3 to 6 is indicated at 56, having a bottom plate 58 within which are insulatedly sealed terminals 60, 62 and 64, of which the terminals 60 and 64 carry contacts 66 and 68 respectively for cooperation with the contacts carried by the contact arm. The inner end of terminal 62 serves as a pivotal support for the contact arm and also as an electrical connection thereto. The terminal 62 is secured to the base of a U-shaped member 70, the upright arms 72 and 74 of which are extended longitudinally to serve as the tensioning support for the contact arm supporting and actuating means. In this embodiment of the invention, ribbons rather than wires are employed for support and actuation of the contact arm, as ribbons have greater strength in relation to flexibility than do wires. Also, instead of passing through holes in the contact arm 76, the crossed ribbons are secured, as by welding, to the contact arm and could therefore be formed of two parts rather than as a single piece. Two parts of one ribbon are identified by reference numerals 78a and 78b and the corresponding parts of the other ribbon are identified as 80a

and 80b. The ends of the ribbon parts 78a and 80a are secured to longitudinally spaced points of the upper end of upright arm 72 and the other ends of these parts are secured to opposite ends of contact arm 76, the part 78a overlying at the cross-over point A the part 80a. One end of ribbon part 78b is secured to the contact arm 76 as a continuation of part 78a and, similarly, one end of ribbon part 80b is secured to the contact arm 76 as a continuation of part 80a, the other ends of the parts 78b and 80b being secured to spaced points on the upper end of the other upright arm 74 and part 80b overlying part 78b at the cross-over point B. Preferably, the ends of the ribbons are attached to the ends of the upright arms by means of beads 82 which permit adjustment of the tension in the ribbons.

In order to actuate the above described switch while maintaining the parts within a hermetically sealed casing, the structure now to be described is employed. Thin walled phosphor bronze tubing 84 is sealed within an aperture 86 in the upper wall of the casing 56 and into this tubing extends a strip 88 which, above the casing, is twisted through 90° and bent through 90° to provide a longitudinally extending arm 90 for actuation by external means. The tubing 84 within the casing is flattened about the strip 88 and sealing cement, indicated at 92, is provided between the strip 88 and the walls of the tube at the point of flattening. The flattened tube 84 serves as a sealed pivot for an arm 94 within the casing. The arm 94 extends longitudinally to a point slightly beyond the transverse section within which are disposed the cross-over points A and B. An inverted L-shaped member 96 is secured to the free end of the strip 94 (see Fig. 6) and the lower end of this piece 96 is bent back upon itself to form a rounded end 98 for engagement with ribbon section 80b adjacent the cross-over point B. Adjacent the tube 84 the strip 94 is twisted through 90° to provide a horizontal section 100 and is then bent downwardly and upwardly to provide a U-shaped part 102 into which the flattened end of the tube 84 is received and cemented. With the above described construction, when the free end of the arm 90 is moved toward the casing by external actuating means, the flattened phosphor bronze tubing flexes at its end, rocking the arm 94 about a horizontal axis passing through the line of flexure of the tubing and consequently moving the end 98 up or down to vary the spacing at point B.

In the particular construction of switch illustrated in Figs. 3 to 6, the normal spacing of the ribbons at point B is substantially greater than that at point A and the fixed contacts 66 and 68 are positioned to permit but slight movement of the contact arm 76. The arm is thus biased into position to close the circuit between terminals 62 and 64. Upon downward pressure on ribbon part 80b at point B, the arm will snap into position to close the circuit between terminals 62 and 60 but upon release of the pressure on ribbon part 80b will snap back to its biased position.

For convenience of mounting and supporting the switch, the side walls of the casing 56 are connected near opposite ends of the device by tubing 104 and 106, both ends of each piece of tubing being hermetically sealed to the casing.

The above described construction provides a quick acting snap switch of small size and one in which all moving parts are protected from the atmosphere or from handling. The hermetically sealed pivotal arrangement utilizing a thin

walled, elastic tubing permits ready actuation by externally mounted operating fingers. Obviously, various changes and additions could be made to the particular structure illustrated. For example, additional fixed contacts for cooperation with the contact arm 76 could be provided and the pivotal support of the contact arm could be eliminated if desired. The pivotal support, however, provides insurance against vibration effects and also insures a positive symmetrical action of both contacts.

In Fig. 7 a switch having features in common with the hermetically sealed switch of Figs. 3 to 6 is illustrated. In this embodiment of the invention actuation is effected by rotation of a part to which the ends of the crossed wires or ribbons are attached. The switch comprises a base plate 108 adjacent one edge of which is fixedly mounted an end wall 110 to which one end of ribbons 112a and 114a are attached under tension. Adjacent the opposite edge of plate 108 a bar 116 is pivotally mounted and one end of ribbons 112b and 114b are attached under tension to this bar. The other ends of the ribbons are connected as in the embodiment of the invention illustrated in Figs. 3 to 6, to spaced points of a contact arm 118. In this particular construction the central pivotal support for the contact arm is omitted, the contact arm being supported solely by the tensioned ribbons. Upper and lower fixed contacts for cooperation with contacts carried on the ends of the contact arm are mounted on suitable brackets secured to the plate 108. Bar 116 is so mounted that its axis of rotation passes through the cross-over points of the ribbons. Upstanding from the base 108 is a member 120 carrying a bearing within which is rotatably mounted a rock shaft 122. Bar 116 is fixed at 124 to one end of shaft 122 and a downwardly depending arm 126 is fixed to the other end of the shaft. Arm 126 is biased by a spring 137 against a fixed stop 138 formed integral with the base 108 or otherwise fixedly mounted with respect thereto. Contact arm 118 is biased by original spacing of the ribbons at the cross-over points into the position shown in Fig. 7, that is with the contact on the lefthand end of the arm in engagement with the lower fixed contact. Thus when the arm 126 is engaged as by an operating finger 139 and moved in the direction of the arrow, bar 116 rocks in a direction to cause clockwise rotation of the contact arm. Return of the arm 126 to initial position permits contact arm 118 to rotate counterclockwise back to its biased position. Thus if leads 130, 132, 134 and 136 are connected to the fixed contacts with leads 130 and 134 being connected to the upper contacts and leads 132 and 136 to the lower contacts, a circuit is closed between leads 130 and 136 in one position of the contact arm and between leads 132 and 134 in the other position of the contact arm. If leads 134 and 136 are connected together, the switch operates, like that of Fig. 1, as a single throw, double pole switch with twice the rate of contact break and twice the contact clearance of ordinary single throw, double pole switches. With the circuit as shown, the switch operates to close either of two circuits, depending upon the position of the contact arm. Spring 137 insures return of the bar 116 to initial position upon release of pressure on the arm 126.

In Fig. 8 a sequential switch embodying the invention is more or less diagrammatically illustrated. The switch comprises a rectangular framework consisting of longitudinal parallel

sides 140 and 141 and transverse parallel sides 142 and 144, together with four contact arms 146, 148, 150 and 152, all floatingly suspended by a single tensioned wire 154. The wire is connected at its ends under tension to two spaced points on side 144, crosses and passes through spaced holes in contact arm 146, then crosses again and passes through spaced holes in contact arm 148 and similarly through spaced holes in contact arms 150 and 152 with crossings intermediate the contact arms. The central stretch of the wire extends along the outer surface of the side 142 after passing through spaced holes in that side. Between each of the contact arms the overlying section of wire extends downward to the right as viewed in Fig. 8.

Insulatedly mounted on the side 141 above the contacts carried on the ends of the contact arms 146 and 150 are fixed contact carrying members 156 and 160, and, similarly, insulatedly mounted on the side 141 below the contacts carried on the ends of the contact arms 148 and 152 are fixed contact carrying members 158 and 162. External leads 164, 166, 168 and 170 are respectively connected to the fixed contact carrying members 156, 158, 160 and 162. Fixed stops for the contact arms are mounted on the side 141 below the ends of contact carrying arms 146 and 150 and above the ends of contact carrying arms 148 and 152. On the side 140 fixed contact carrying members 172 and 176 are insulatedly mounted below the contacts carried on the ends of arms 146 and 150 respectively, and, similarly, fixed contact carrying members 174 and 178 are positioned on side 140 above the contacts carried in the ends of contact arms 148 and 152. Suitable stops are mounted on the side 140 above the ends of contact arms 146 and 150 and below the ends of contact arms 148 and 152. External leads 180, 182, 184 and 186 are connected respectively with contact carrying members 172, 174, 176 and 178. With this arrangement if pressure is applied to the upper stretch of the wire 154 adjacent the cross-over point intermediate the contact arm 146 and the end wall 144 as indicated by the arrow 188, contact arm 146 is rocked in a direction to close the circuit between leads 164 and 180. Movement of the contact arm 146 to this position causes contact arm 148 to rock in the opposite direction to close the circuit between leads 166 and 182 and this movement of contact arm 148 correspondingly causes rocking of contact arm 150 into position to close its circuit, whereupon contact arm 152 is likewise rocked to close its circuit. Thus the single actuation by pressure at the point indicated by arrow 188 causes successive closure of the circuit connected to the contact arms. To reverse the order of closure of the circuits, it is only necessary to press on the upper stretch of the wire 154 adjacent the cross-over point between contact arm 152 and end wall 142, as indicated by the arrow 190. Downward pressure at this point causes successive rockings of arms 152, 150, 148 and 146 to close their respective circuits.

To open the circuits successively, pressure may be exerted on the lower stretch of the wire 154 either at the cross-over between arm 146 and wall 144 or at the cross-over between arm 152 and wall 142 or downward pressure may be applied to the upper stretch of the wire at the cross-over between arms 146 and 148 or between arms 150 and 152. If the stops associated with the contact arms were replaced with insulated contacts and external leads, the switch would operate to suc-

cessively close circuits connected to these contacts instead of to merely open the circuits herefore identified.

The invention has now been described with reference to various embodiments thereof. In each embodiment of the invention flexible crossed wires or ribbons under tension support one or more contact arms, and movement of the contact arm or arms is effected with a snap action upon relative change in spacing of the wires or ribbons at the cross-over points, the change in spacing being effected in any one of a number of ways. In one embodiment of the invention the change in spacing is effected by rotation of the wall supporting the ends of the ribbons, whereas in other embodiments the change in spacing is effected by downward pressure upon the upper stretch of a wire or ribbon adjacent the cross-over point.

It will be apparent from the foregoing description that the invention comprises a positive acting, snap action device which is of simple construction and which insures good separation of contacts for relatively minute movements of an actuating device. The switch lends itself for incorporation within a hermetically sealed enclosure with all the advantages inherent to such construction. A switch constructed, for example, like that illustrated in Figs. 3 to 6, will actuate upon an angular displacement of the operating lever of as little as .015 degree. A switch such as that illustrated in Figs. 1, 2 or 7 will operate upon displacement of the tension wire or ribbon of as little as .002 inch, and one of the constructions of Fig. 8 upon displacement of .010 inch. The dimensions of the switch are not critical nor is it essential that the parts be exactly symmetrical. Ready adjustment is afforded by means of the fixed contacts and stops to insure any desired normal position of the contact arm. Depending upon the geometry of the device and upon the positioning of the contacts and stops, the switch may be made to return to initial position upon release of the actuating pressure or may be made to remain in actuated position upon release of the actuating pressure. Various changes in the particular construction illustrated will occur to those skilled in the art.

The following is claimed:

50. 1. A snap action device comprising a movable arm, flexible threads engaging and at least partially supporting said arm at two spaced points, said threads extending outwardly from their points of engagement with said arm and crossing at points spaced laterally of said arm, means securing the ends of said threads under tension in spaced relation, one of said threads overlying the other at the cross-over point on one side of said arm and underlying the other at the cross-over point at the other side of the arm whereby said arm tends to rotate in one direction or the other, depending upon the relative spacing between the threads at the cross-over points about an axis located between the points of engagement with said threads, fixed means positioned for engagement by said arm for limiting the extent of rotation thereof in each direction, and actuating means for varying the spacing between the threads at a cross-over point to cause rotation of said arm.
55. 2. The snap action device according to claim 1 wherein said threads comprise the sole support of said arm during rotation thereof through a position of unstable equilibrium.
60. 3. The snap action device according to claim 1

wherein said actuating means comprises a member adapted to engage and move one thread toward the other thread adjacent a cross-over point to decrease the spacing between the threads.

4. The snap action device according to claim 1 wherein said actuating means comprise a movable member to spaced points of which one end of each thread is secured under tension and means for moving said member in a direction to vary the spacing between the threads at a cross-over point.

5. The snap action device according to claim 1 wherein the ends of said threads are secured to points so located that the spacing between the threads at the cross-over point on one side of said arm is larger than that at the cross-over point on the other side of said arm whereby said arm has a biased position to which it returns upon release by said actuating means.

6. The snap action device according to claim 1 wherein said threads are ribbons and are fixedly secured to said arm.

7. The snap action device according to claim 1 including at least one other movable arm engaged and at least partially supported at spaced points by said threads, said arm being laterally spaced from said first arm with a cross-over point of said threads located between said arms, the threads extending beyond said second arm and crossing at a location spaced laterally therefrom with the thread that overlies the other at the cross-over point between the arms underlying the other thread at the cross-over point on the other side of the second arm whereby when the spacing between the threads at a cross-over point on the far side of either arm is varied said arms rock sequentially in opposite directions.

8. A snap action switch comprising a movable arm carrying contacts adjacent the ends thereof, flexible threads engaging and at least partially supporting said arm at two spaced points, said threads extending outwardly from their points of engagement with said arm and crossing at points spaced laterally of said arm, means securing the ends of said threads under tension in spaced relation, one of said threads overlying the other at the cross-over point on one side of said arm and underlying the other at the cross-over point at the other side of the arm whereby said arm tends to rotate in one direction or the other, depending upon the relative spacing between the threads at the cross-over points about an axis located between the points of engagement with said threads, at least one fixed contact positioned adjacent each end of said arm for engagement with the contacts carried thereby and for limiting the extent of rotation of the arm, and actuating means for varying the spacing between the threads at a cross-over point to cause rotation of said arm and operation of said contacts.

9. A sequential snap action switch comprising a series of generally parallel contact carrying arms at least partially supported by tensioned threads which engage each arm at spaced points and cross at locations intermediate the arms and at locations beyond the first and last arm of the series, the ends of said threads being secured under tension in spaced relation, one of said threads alternately overlying and underlying the other thread at the cross-over points, and fixed means associated with each arm for limiting the extent of rotation thereof about axes located between the points of engagement of the threads with the arms, said last mentioned means includ-

ing fixed contacts for engagement by the contacts carried by the arms whereby, when the spacing between the threads at a cross-over point is varied in a direction to rock an adjacent arm, rocking of such arm, varies the spacing of the threads at the cross-over point on the other side of that arm and thereby causes the next arm to rock with consequent sequential operation of the arms and contacts associated therewith.

10. A snap action switch comprising a movable arm, fixed wall members disposed on opposite sides of said arm, two flexible threads secured at their ends under tension to spaced points of said wall members and adjacent their midpoints to spaced points of said arm, the threads crossing intermediate said arm and each wall with the thread overlying the other at one cross-over underlying the other at the other cross-over a combined stop and fixed contact positioned adjacent each end of said arm for engagement therewith in opposite angular positions of the arm, electrical connections to said fixed contacts and to said arm, an actuating lever mounted for pivotal movement about an axis generally perpendicular to the plane of rotation of said arm and having a finger at its other end adapted to engage a thread adjacent a cross-over, and means for moving said lever about its pivot to vary the spacing between the threads at that cross-over and thereby cause said arm to snap from one contact closing position to another.

11. The snap action switch according to claim 10 wherein said arm, threads, contacts and lever are mounted within a hermetically sealed casing and wherein the pivotal mounting of said lever comprises a thin walled elastic tube of impervious material hermetically sealed at one end in an aperture in the casing wall and extending into the casing, the tubing being flattened at its other end, an end of said lever being secured to the flattened end of said tubing, and said means for moving said lever comprising a member extending into said tubing and gripped by the flattened portion thereof, whereby movement of said member flexes said tubing and rocks said lever.

12. The snap action device according to claim 11 wherein said member is generally L-shaped with one part extending into said tubing and another part extending generally parallel to said lever and in the same direction from the pivot whereby said lever follows the movement of said last mentioned part of said L-shaped member.

13. The snap action switch according to claim 10 wherein said threads are narrow ribbons secured along their flat sides to said arm.

14. The snap action switch according to claim 10 wherein said electrical connection to said arm comprises a fixed member engaging the arm intermediate the points of attachment of said threads and serving also as a pivot for said arm.

15. The snap action switch according to claim 10 wherein said finger engages the overlying thread at a cross-over and the ends of said threads are secured to said walls at points so located that the spacing between the threads at the cross-over adjacent the finger of said lever is larger than that at the other cross-over, whereby said arm is biased into one contact closing position and returns to that position upon reduction in pressure of the finger on the thread engaged thereby.
